COMBINATION PIVOTING AND SLIDING
BLOCK FIREARM ACTIONJohn Le B. Arbuckle, Sunbury, Ohio, assignor of
one-half to Hugh E. Grashel, Gahanna, Ohio

Application November 22, 1950, Serial No. 197,154

4 Claims. (Cl. 42—34)

1

The present invention relates to firearms, and has particular reference to an improved firing action to be used in connection with precision-type single shot target rifles.

This invention has for its primary objective the provision of an improved firearm action which is particularly adapted for use in connection with precision built target rifles, and which is characterized by structurally rugged and durable elements which function one with the other to provide a precision-type firing mechanism devoid of undesired play and which greatly reduces the amount of wear between relatively movable parts of the mechanism in comparison with previously known types of firearm actions.

Another object of this invention is to provide an action for firearms wherein the separate elements or parts of the action are readily accessible for purposes of disassembly, cleaning, repair, or replacement.

It is a further object of the present invention to provide a firearm action which comprises a stationary frame which is formed at one end to receive the chambered end portion of a barrel and at its opposite end to receive the shank of a stock, and which detachably mounts a combination of moving elements which may be quickly and easily detached from the frame and the firearm as a unit through the simple removal of a single pivot pin to provide access to the working mechanisms of the firearm to facilitate cleaning, adjustment, or replacement of the elements of the actual firing mechanism without necessitating the complete disassembly of the firearm.

Yet another object of this invention is to provide a firearm action which embodies a trigger and an associated trigger spring mechanism which is adjustable to vary the amount of manually applied force required to move the trigger between its cocked and firing positions.

These and various additional objects and advantages will become more readily apparent with a further understanding of the present invention which may be had by reference to the following description and the accompanying drawings, wherein:

Fig. 1 is a top plan view of a firearm action formed in accordance with the present invention;

Fig. 2 is a side elevational view thereof;

Fig. 3 is a medial longitudinal vertical sectional view taken through the firing mechanism and showing the various parts thereof in their cartridge-firing positions;

2

Fig. 4 is a similar view showing the action in an intermediate cocking position;

Fig. 5 is a similar view of the action with the various parts thereof occupying their cartridge-extracting and receiving positions;

Fig. 6 is a similar view of the action in its fully cocked position with the associated safety in a safe position;

Figs. 7—9 are detailed transverse vertical sectional views taken along the lines 7—7, 8—8, and 9—9, respectively, of Fig. 3;

Fig. 10 is a detailed horizontal view along the line 10—10 of Fig. 3; and

Figs. 11—13 are detailed perspective views of the pivoting block, sliding block, and cocking lever, respectively, of the present action.

Fig. 14 is a medial longitudinal vertical sectional view of the extractor engaging a cartridge.

Fig. 15 is a transverse vertical sectional view of the extractor engaging a cartridge.

Referring to the drawings, the numeral 20 designates generally the stationary frame portion of the present firearm action. At its forward end, the frame 20 is formed with a cylindrical boss formation 22 in which is formed a threaded barrel-receiving opening 23 for the threaded reception of the chambered end of a rifle barrel 24. At its rearward end, the frame 20 is formed with a substantially rectangular and inwardly tapered stock-receiving opening or recess 25 which receives the shank portion 26 of a shoulder stock 27. Intermediate its ends, the frame 20 is formed with transversely spaced vertically extending side walls 28 defining an open-ended vertically arranged chamber between the barrel-receiving boss 22 and stock-receiving region 25. Advantageously, the stock-receiving region 25 of the frame 20 is provided with an outwardly projecting and internally screw-threaded attachment tube 30 which is arranged to extend within a cooperative opening formed in the shank of the stock 27 and to receive a cooperatively screw-threaded shaft or rod 32 which extends through the stock 27 and into the screw-threaded chamber of the tube 30 to securely fasten the stock 27 to the rear end of the frame 20. In this manner, the stock 27 may be easily detached from the remaining portion of the firearm simply by disconnecting the single rod 32 from the screw-threaded extension 30 of the frame.

Extending transversely between the spaced side walls 28 of the frame, below the barrel-receiving opening 23, is a smooth-surfaced pivot pin 34. Preferably, the pin 34 is provided at one end with an enlarged head 35 which is slotted to receive

the driving head of a screwdriver, and which is provided on its periphery with an arcuate recess 36 arranged to be brought into alignment with a segment of the circular head portion of a lock screw 37 to permit removal of the pin 34 from the frame. The lock screw 37 functions to prevent accidental removal of the pin 34 when the latter is rotated to move the slot 36 out of registration with the head of the lock screw, and it will be understood that this assembly is common to many types of firearms, and as such, constitutes no particular part of the present invention. Advantageously, the depending side walls 28, in the region of the pin 34, are provided on their inner sides with spaced wear plates or blocks 38 which are rigidly joined with the side walls 28, but which may be removed for replacement if so desired. Extending between the wear blocks 38 of the frame are a pair of transversely spaced ears 40 formed integrally with a pivoting block 42. The spaced ears 40 are provided with transversely aligned openings 44 through which the pivot pin 34 extends to support the pivoting block 42 for pivotal swinging movement. The block 42, in addition to the spaced ears, is formed to provide a perpendicularly related breechblock portion 46 which, when the block occupies its battery position, lies in abutting engagement with the walls of the cylindrical boss formation 22 of the frame which define the barrel-receiving opening 23. The flat forward face of the breechblock portion of block 42, in operation, abuts the cap end of a cartridge when the latter is positioned within the chamber of the barrel 24. The rear side surface of the block 42 is formed in its intermediate region with an arcuate recess 48, and is provided at its lower end with a rearwardly projecting and arcuately rounded cam surface 50.

Pivots carried upon the pin 34 between the transversely spaced ears 40 of the block 42 is a manually operated cocking lever 52. As shown in detail in Fig. 13, the cocking lever 52 is provided with an intermediate tubular formation 54 through which is formed a transversely extended bore 56 for the reception of the pivot pin 34. Additionally, the cocking lever is provided with a depending handle arm 58 by which the cocking lever may be swung or rocked about the pivot pin 34. Normally, the handle 58 extends rearwardly from the bottom of the frame 20, and when occupying a cocked position, is disposed in substantially parallel relation to the shank portion of the stock 27. The cocking lever 52 is further provided with an outwardly projecting lip 60 which, as shown particularly in Fig. 4 of the drawings, is arranged to engage a shoulder 62 formed on the pivoting block 42 between the ears 40 to swing the pivoting block in a clockwise direction about the pivot pin 34 and out of its battery position in abutment with the chambered end of the barrel. The cocking lever 52 is further provided with a second outwardly extending block-like arm 64 of relatively greater width than the intermediate region 54 of the cocking lever, and which extends rearwardly of the vertical chamber of the frame and terminates at its outer end in a pair of transversely spaced ears 65 which rotatably support a pair of rectangular guide blocks 66 projecting laterally outwardly from either side of the block 64.

The guide blocks 66 carried on the cocking lever 52 are slidably received in a pair of spaced parallel guide tracks 68 formed on the inner side surfaces of a sliding block 70. The sliding block 70 is provided with transversely spaced side walls 72

at its forward end, and terminates at its rearward end in a chambered yoke region 74. The yoke region 74 of the sliding block is rounded on its upper rear side, as at 76, in order that the block may clear the rear side wall 78 of the vertically arranged frame chamber. In addition to the spaced horizontally disposed guide track 68, the sliding block is provided with spaced parallel and vertically arranged guide tracks 80 which slidably receive vertically arranged and laterally projecting guide formations 82 formed on either side of the pivoting block 42. Thus the pivoting block 42 fits within the vertical chamber defined by the side walls 72 of the sliding block. Rearwardly of the spaced side walls 72, the sliding block, in its yoke region 74, is recessed to provide a dome-shaped hammer-receiving chamber 84. Extending between the spaced side walls 72 of the sliding block are a pair of cylindrical spacer projections 86 formed on either side of a vertically arranged hammer 88. The transversely extending spacer projections 86 are provided with a bore for the reception of a smooth-surfaced hammer-supporting pin 90 which extends between the spaced side walls 72 of the sliding block. The pin 90 is provided at one end with an enlarged tapered head 92 which fits within a tapered socket 94 formed in one of the side walls 72 of the sliding block, while the opposite end of the pin 90 extends within an opening 96 formed in the opposite side wall 72 of the sliding block. Advantageously, the side wall 72, which is provided with the head-receiving socket 94, may also be formed with an adjacent lock screw opening 98 for the reception of a lock screw, not shown, of the type indicated at 37, which functions to hold the headed region of the hammer 90 in a flush position with respect to the outer surface of the sliding block and against withdrawal from the side wall 72 of the sliding block. The hammer pin 90 functions to pivotally support the hammer 88 and its associated cylindrical spacer projections 86. Wound about one of the projections 86 is a torsion spring 100 which has one of its ends held within an opening, as at 102, formed in the hammer 88, and its opposite end positioned within an opening formed in the adjacent side wall 72 of the sliding block 70. The hammer 88 is formed on its upper forward side with a flat striking face 104 which is arranged to swing into striking engagement with the rearward end of a firing pin 106 which extends longitudinally through a suitably chambered opening formed in the upper head portion of the pivoting block 42. The firing pin 106 is formed at its rearward end with a relatively enlarged cylindrical portion 108 and terminates at its forward end in a relatively reduced cylindrical portion 110 arranged to project outwardly from the flat breechblock portion 46 of the pivoting block for firing engagement with the cap of a cartridge positioned within the chamber of the barrel 24. The relatively enlarged cylindrical portion 108 of the firing pin is provided on one side with an elongated slot 112 into which extends the inner end of a retaining screw 114 extending through one side of the head portion of the pivoting block 42. The retaining screw 114 holds the firing pin 106 within the chamber of the pivoting block 42 to permit limited longitudinal sliding movement of the firing pin within the pivoting block, and further provides for removal of the firing pin in its entirety from the pivoting block when access thereto is desired. Normally, with the striking face 104 of the hammer 88 in engagement with the rear end of the

firing pin 106, the forward pointed extremity of the firing pin projects outwardly beyond the breechblock portion of the pivoting block, as shown in Fig. 11, but as the striking face 104 of the hammer 88 is moved out of engagement with the rear end of the firing pin, the same moves rearwardly of the pivoting block and projects slightly beyond the rearward flat face thereof.

The hammer 88 is further formed to provide a cocking abutment 114 which projects in right angular relation to the firing face 104 for engagement with the cam projection 50 formed on the pivoting block 42. Relative downward movement of the sliding block 70 with respect to the pivoting block 42 functions to engage the cocking projection 114 on the hammer with the cam face 50 of the pivoting block to swing the hammer 88 about its pivot pin 90 against the action of the torsion spring 100. Further, the hammer 88 is formed on its lower side with a sear-receiving shoulder 116 which is engageable with an outwardly projecting sear 118 formed on a trigger 120 to releasably hold the hammer 88 in its cocked position. The trigger 120 is formed with a centrally disposed opening through which extends a pivot pin 122 carried between the side walls 72 of the sliding block 70. As with the hammer pin 90, the trigger-supporting pin 122 is received within transversely aligned openings formed in the respective side walls of the sliding block, with one end of the pin 122 being headed and received within a tapered socket 124 formed in the lower side of one of the side walls 72. The trigger 120 is formed to provide a downwardly projecting arcuate finger-receiving lever 126 which is formed on its rear side with an enlarged vertically arranged chambered boss 128 through which extends a cylindrical bore 130. The cylindrical bore 130 of the trigger screw-threadedly receives at its lower end a threaded plug 132, the inner end of which abuts one end of a coiled compression spring 134 whose opposite end engages a plunger 136 which projects outwardly from the opposite end of the tubular boss 128 for engagement with a cross piece 138 formed on the sliding block 70 between the side walls 72. It will be noted that the upper end of the tubular extension 128 of the trigger is normally spaced from the lower surface of the cross piece 138 to permit limited pivotal movement of the trigger in response to manually applied forces. By increasing or decreasing the tension upon the compression spring 134, by adjustment of the screw 132, the forces necessary to rock the trigger 126 about the pin 122 may be correspondingly increased or decreased to determine the "trigger pull" of the action.

As shown particularly in Fig. 6 of the drawings, the hammer 88 is provided upon its upper surface with a shouldered detent 140 which is arranged to receive a safety plunger 142 extending through the stock-adjoining region 25 of the frame 20. The safety plunger 142 is slidably carried within a cylindrical chamber formed in the stock-engaging region of the frame, and is formed at its rear end with rack teeth 144 carried in meshing engagement with the teeth 146 formed on a segment of the lower surface of a tubular casing 148. The casing 148 is rotatably mounted on a pin 150 which extends through the casing 148 and an adjoining stationary bearing sleeve 152 carried on the upper surface of the stock-adjoining portion of the frame. The shaft 150 is headed at one end, as at 156, and provided at its opposite end with a screw-threaded region, not shown, which

is threaded with a headed nut 158 carried at the opposite end of the casing 148. The casing 148, on its outer surface, is provided with an actuating lever 160 by which the casing 148 may be rotated to move the safety plunger 142 into and out of engagement with the detent 140 on the hammer 88. Advantageously, the leading end of the safety plunger 142 is beveled and arranged to wedge against the shouldered surface of the detent 140 on the hammer in a manner to swing the hammer 88 slightly in a clockwise direction as viewed from Fig. 6 and to move the sear-receiving shoulder 116 slightly out of engagement with the sear 118 of the trigger. Thus, when the safety is applied, the tension of the hammer spring is removed from the sear 118 and is taken up by the safety plunger 142 to permit the trigger 120 to be freely moved without releasing the hammer.

As shown particularly in Fig. 7 of the drawings, the frame 20 is channeled along its inner side walls to receive an extractor 162 within guide slots 164 disposed below the barrel-receiving boss 22. The extractor 162 comprises a vertically arranged arm 166 which is arcuately recessed at its upper end, as at 168, and which is chambered to receive a spring-pressed cartridge-engaging lip 170 which projects upwardly from the extractor for engagement with the extractor groove 172 formed on a rimless-type cartridge 174. Additionally, the extractor 162 is formed with laterally extended guide legs which are slidably received within the guides 164 of the frame to permit straight longitudinal sliding movement of the extractor. The separate legs 176 are slotted a distance inwardly from their outer ends and join with one another in a cross web 178 which is arranged to be engaged by the projection 60 formed on the cocking lever 52 substantially immediately following the engagement of the projection 60 with the shoulder 62 of the pivoting block 42. Thus, the extractor 162 is moved rearwardly out of engagement with the barrel-receiving boss 22 of the frame by the swinging movement of the cocking lever 52, immediately following engagement of the pivoting block 42 by the projection 60 of the cocking lever.

Referring particularly to Figs. 7 and 10 of the drawings, it will be noted that the central portion 54 of the cocking lever 52 is reduced on one side to provide a cylindrical sleeve 184 around which is wound a torsion spring 186. Adjacent to the sleeve 184 of the cocking lever is a cylindrical spanner nut 188 which is rotatably carried within an opening formed in one of the ears 40 of the pivoting block 42. The nut 188 receives the opposite end of the torsion spring 186, and is provided upon its outer side wall with a plurality of wrench-receiving openings 190 by which the nut 188 may be located to adjust the tension of the torsion spring 186. A locking screw 192 is provided between the nut 188 and the ear 40 of the pivoting block 42 to hold the nut 188 in its desired adjusted position. The opposite end of the torsion spring 186 fits within an opening formed in the central portion 54 of the cocking lever and functions to urge the cocking lever 52 to its closed position, as shown in Figs. 2 and 3 of the drawings, in substantial parallelism with respect to the shank 26 of the stock. Thus, movement of the cocking lever 52 is biased between the positions shown in Figs. 3 and 4, wherein the sliding block 70 is initially moved downwardly with respect to the pivoting block 42. In this manner, the cocking lever 52 and the sliding block

70 are prevented from loosely falling downwardly out of their battery positions, and by reason of the adjustable nature of the nut 183, the tension of the torsion spring 186 may be adjusted to assure the return of the cocking lever to its battery position and the prevention of such lever from sliding downwardly by gravity.

In operation, assuming the chamber of the barrel to be empty, and the hammer 88 to occupy its fired position as shown in Fig. 3, the action is cocked by swinging the handle 58 of the cocking lever in a clockwise direction to slide the sliding block 70 downwardly behind the pivoting block 42, thus moving the hammer 88 to its cocked position as the projection 114 of the hammer slides over the cam face 50 of the pivoting block. Thereupon, the pivoting block is engaged by the lip 60 of the cocking lever and swings backwardly in a clockwise direction to gain access to the chamber of the barrel 24, whereupon the cartridge 74 is inserted within the chamber of the barrel and the cocking lever 52 returned to its battery position as shown in Fig. 6. In this position, the sear-engaging lip 116 of the hammer is normally held by the sear 118 of the trigger. If desired, the safety plunger 142 may be brought into engagement with the detent 140 of the hammer by rocking the lever 160 backwardly. With the safety applied, as shown in Fig. 6, the tension of the hammer spring 100 is removed from the sear 118 due to the slight movement of the hammer 88 in a clockwise direction as viewed from Fig. 6, by reason of the beveled outer end of the plunger 142. When it is desired to fire the action, the safety plunger 142 is retracted by pushing the lever 160 forwardly to permit the sear-receiving lip 116 of the hammer to become engaged with the sear 118 of the trigger. Thereafter, the trigger 120 may be pulled upon to release the hammer 88 and permit the striking face 40 thereof to engage the firing pin 106.

After firing, the cocking procedure is repeated, whereupon the extractor 162 functions to move the fired cartridge 174 rearwardly out of the chamber of the barrel by reason of the engagement of the spring-pressed lip 170 with the groove 172 of the cartridge and the rearward shifting of the extractor by engagement of the projection 60 of the cocking lever with the shoulder 178 of the extractor. With the action in its open position as shown in Fig. 5, the fired cartridge may be removed and replaced with a live cartridge to once again condition the firearm for firing.

While a single preferred embodiment of the invention has been disclosed in detail, it will be understood that various modifications with regard to constructional details may be resorted to without departing from the spirit of the invention or the scope of the following claims.

I claim:

1. In a firearm: a vertically slotted frame chambered at one end to receive a barrel; a pivoting block pivotally carried in said frame for swinging movement into and out of abutting engagement with the chambered barrel-receiving portion of said frame, said pivoting block being formed with a cocking shoulder; a firing pin carried within said pivoting block for limited longitudinal sliding movement and arranged to project outwardly on either side of said pivoting block; a sliding block positioned adjacent to one side of said pivoting block and slidably carried by said pivoting block for limited vertical movement with respect to said pivoting block; a hammer pivotally carried within said sliding

block and having a cocking projection thereon engageable with the cocking shoulder of said pivoting block upon relative vertical sliding movement between said pivoting and sliding blocks for swinging said hammer from a firing position to a cocked position within said sliding block, said hammer, when occupying its firing position, being engageable with said firing pin to project the latter outwardly from the side of said pivoting block adjacent the chambered portion of said frame; spring means connected between said hammer and said sliding block for urging said hammer to its firing position; a trigger pivotally mounted in said sliding block and having a finger-receiving lever and a sear engageable with said hammer to releasably hold said hammer in its cocked position, said trigger being pivotally movable in said sliding block to engage or disengage the sear with or from said hammer; adjustable tension spring means carried between said trigger and said sliding block and urging said trigger to swing to a position to engage the sear with said hammer; and a manually-operable cocking lever pivotally carried in said frame along the pivotal axis of said pivoting block and slidably connected with said sliding block and having a projection thereon engageable with said pivoting block, said cocking lever being movable to slide said sliding block vertically with respect to said pivoting block and to swing the latter into and out of abutting engagement with the chambered portion of said frame.

2. In a firearm firing mechanism: a frame having a barrel-receiving chamber; a compound breechblock assembly comprising a first pivoting block pivotally mounted in said frame for swinging movement between a position abutting one end of the barrel-receiving chamber of said frame and a second position providing unobstructed access to said chamber, and a second sliding block slidably carried by said pivoting block and pivotally movable therewith, said sliding block being positioned on the side of said pivoting block opposite the barrel-receiving chamber of said frame and being movable vertically with respect to said pivoting block; a firing pin extending through and slidably in said pivoting block; a striking hammer pivotally carried in said sliding block for swinging movement between cocked and firing positions; means stationarily carried by said pivoting block for moving said hammer between its firing and cocked positions upon relative downward sliding movement of said sliding block with respect to said pivoting block; and a cocking lever pivotally mounted in said frame and movable in one direction to first slide said sliding block downwardly with respect to said pivoting block and to thereafter swing said pivoting block to its position away from the barrel-receiving chamber of said frame.

3. In a firearm firing mechanism: a frame formed with a chamber to receive a barrel; a compound breechblock assembly pivotally mounted within said frame for swinging movement into and out of registration with the barrel-receiving chamber of said frame, said breechblock assembly including a first pivoting block section arranged to pivotally swing between a first position adjacent to the chamber of said frame and a second position providing unobstructed access to the chamber of said frame, and a second sliding block section slidably carried on the pivoting block section for relative

vertical movement with respect thereto; a firing pin extending through the pivoting block section of said breechblock assembly and carried therein for limited longitudinal sliding movement; a cam abutment on the pivoting block section of said breechblock assembly; a hammer pivotally mounted within the sliding block section for swinging movement between firing and cocked positions, said hammer, when occupying its firing position, being engageable with one end of said firing pin; a cam follower on said hammer engageable with said cam abutment upon relative downward vertical movement of the sliding block section with respect to the pivoting block section for moving said hammer between its firing and cocked positions; spring means connected with said hammer and resiliently urging the latter toward its firing position; manually-operable trigger means pivotally carried within the sliding block section of said breechblock assembly and having a sear thereon engageable with said hammer for releasably holding the latter in its cocked position; and a manually-operable cocking lever pivotally mounted within said frame and slidably connected with the sliding block section of said breechblock assembly, said cocking lever having a projection thereon engageable with the pivoting block section of said breechblock assembly for swinging the latter within said frame, said cocking lever being movable in one direction to first slide the sliding block section relatively downwardly with respect to the pivoting block section and for thereafter swinging said pivoting and sliding block sections into and out of registration with the chamber of said frame.

4. In a firearm firing mechanism: a frame having a barrel-receiving chamber; a compound breechblock assembly comprising a first pivoting block pivotally mounted in said frame for swinging movement between a position abutting one

end of the barrel-receiving chamber of said frame and a second position providing unobstructed access to said chamber, and a second sliding block slidably carried by said pivoting block and pivotally movable therewith, said sliding block being positioned on the side of said pivoting block opposite the barrel-receiving chamber of said frame and being movable vertically with respect to said pivoting block; a firing pin extending through and slidably in said pivoting block; a striking hammer pivotally carried in said sliding block for swinging movement between cocked and firing positions; means stationarily carried by said pivoting block for moving said hammer between its firing and cocked positions upon relative downward sliding movement of said sliding block with respect to said pivoting block; a cocking lever pivotally mounted in said frame and movable in one direction to first slide said sliding block downwardly with respect to said rolling block and to thereafter swing said pivoting block to its position away from the barrel-receiving chamber of said frame; and spring means connected with said cocking lever for urging the latter to move in the opposite direction.

JOHN LE B. ARBUCKLE.
